(57) **CLAIM**

The ornamental design for LCD TV (MOB), as shown and described.

DESCRIPTION

FIG. 1 is a perspective view of a LCD TV (MOB) in accordance with my invention thereof;

FIG. 2 is a top view thereof, in an open position;

FIG. 3 is a front view thereof, in an open position;

FIG. 4 is a bottom view thereof, in an open position;

FIG. 5 is a right side view thereof, in an open position;

FIG. 6 is a back view thereof, in an open position;

FIG. 7 is a left side view thereof, in an open position;

FIG. 8 is a top view thereof, in a closed position;

FIG. 9 is a front view thereof, in a closed position;

FIG. 10 is bottom view thereof, in a closed position;

FIG. 11 is a right side view thereof, in a closed position;

FIG. 12 is a back view thereof, in a closed position; and,

FIG. 13 is a left side view thereof, in a closed position.
